UNITED STATES PATENT OFFICE.

CARL F. ABERLE, OF ST. LOUIS, MISSOURI.

BUILDING CONSTRUCTION.

Application filed February 10, 1926. Serial No. 87,267.

This invention relates to building construction.

An object of the invention is to provide an improved building construction, the walls of which comprise inner and outer facings having projections extending toward the facings, respectively, in overlapping and superimposed relationship in a manner leaving an intervening space between the facings which space is longitudinally and vertically continuous throughout the length and height of the walls, except in places where doors or windows or other similar openings are provided through the walls.

Another object of the invention is to provide a series of fabricated units, hereinafter designated stones, which stones except at the corners and terminal portions of the walls are of approximately duplicate construction, thus facilitating and expediting replacement thereof in the walls; while the outer and inner corner stones are, respectively, of approximately duplicate construction, the various stones being provided with lateral projections so that the projections on the stones of the inner and outer facings overlap but terminate short of the inner faces of the opposite stones, leaving the continuous air space between the wall facings.

Reference is made to my prior Patent No. 1,551,776, issued September 1, 1925.

Other objects will appear from the following description, reference being made to the drawings, in which—

Figs. 1 and 2 are plan views of two superimposed layers of stones forming a wall having a door opening and the connected wall having a window opening.

Fig. 3 is a perspective view of a corner stone.

Fig. 4 is a perspective view of another corner stone.

The stones are hardened plastic material and are made in series, the stones of each series being duplicates. The outer corner stone 1 of one layer of the outer wall facing is an integral structure comprising a relatively long arm 2, a relatively short arm 3, the outer surfaces of which form the intersecting wall surfaces at the corners, and the projection 4 extending inwardly from

the arm 2 approximately midway of its length. In one layer, the arms 2 form the outer surface of a wall intersecting the outer surfaces of the wall formed by the arms 3. In the next layer the position of the stone is reversed, placing the arm 3 upon the arm 2 of the next lower stone and the arm 2 upon the arm 3 of the next lower stone and extending well beyond it, as will be understood by conceiving Figs. 1 and 2 superimposed.

For the inner wall facing at the corners, the corner forming stones are provided comprising an arm 5 having at one end an integral projection 6 laid to extend toward and spaced an appropriate distance from the outer wall facing, leaving a relatively wide opening between all parts of the inner and outer wall facings.

The corner stones 5—6 alternate vertically with other stones which may be of different series and are in both connected walls at the corners but in alternating layers, so that the projections 6 alternate with and bear upon the projections 4 of the stones 1, and vice versa. Thus, both corner facings or inner walls have alternate connection with both corner facings of outer walls by means of the superimposing projections 4 and 6, leaving a continuous air space vertically and laterally around the corner.

Continuations of the inner and outer wall facings may be formed by duplicate stones 7 arranged in continuation of and to overlap the arms 2 alternately and to extend from and to alternate with the stones 5—6 alternately. These stones 7 have integral projections 8, and the stones 7 of one facing are laid in a relationship to the stones 7 of the other facing so that the abutting ends of the stones 7 of one facing are opposite the projections 8 of the other facing alternately. By this broken joint arrangement, the projections 8 of each facing rest upon the projections 8 of the other facing, leaving a continuous vertical and longitudinal air space between the two wall facings. The stones of each facing may be interlocked by filling cavities in the abutting ends of the stones with mortar 9.

The corner stones 5—6 may be used as the

corner stones of an inner facing or to extend a wall from the outer facing, and still leave the vertically and laterally continuous air space of one wall communicating with the 5 air space of all other walls.

For forming the ends of the walls at the sides of door openings outer series of stones is provided, each comprising an arm 12 in continuation of the outer wall facing 10 and a projection 13 extending into contact with the outer surface of the inner wall facing. The stones 12-13 alternate vertically with any other stones of the outer wall facing. The stones 12-13 have corner 15 notches 14 to receive and retain a part of the door frame. A series of inner wall facing stones is provided, each comprising an arm 15 in continuation of the inner wall facing and a projection 16 alternating in vertical 20 series with the projections 13 and contacting with the inner surface of the outer facing stones. The projections 16 are provided with notches 17 matching the vertically adjacent portions of the notches 14. The walls 25 at the sides of the door rest upon stone door sills 19.

These building stones are capable of use to construct buildings of a wide variety of designs and walls of different thicknesses, 30 lengths and shapes.

What I claim and desire to secure by Letters Patent is:—

1. In a building wall, a series of angular corner stones each comprising a relatively long arm and a relatively short arm of approximately equal thickness throughout their length and integrally united by a thickened portion, and a lateral projection from the inner side of the long arm approximately 35 midway of its length, said stones being arranged to be superimposed at the corner of united walls with the long arms and short arms alternating one above the other and having their ends breaking joint in a relationship 40 in which the ends of the short arms are intermediate the planes of the sides of said projections of upper and lower stones.

2. In a building wall, a series of angular corner stones each comprising a relatively long arm and a relatively short arm of approximately equal thickness throughout their length and integrally united by a thickened portion, a lateral projection from the inner side of the long arm approximately midway 50 of its length, said stones being arranged to be superimposed at the corner of united walls with the long arms and short arms alternating one above the other and having their ends breaking joint in a relationship 55 in which the ends of the short arms are intermediate the planes of the sides of said projections of upper and lower stones, inner wall facing stones spaced from said first 60 named stones, and projections on each of

said inner facing stones bearing upon the 65 projections on said first named stones and terminating out of contact with the inner faces of said first named stones.

3. In a building wall, a series of angular corner stones each comprising a relatively long arm and a relatively short arm of approximately equal thickness throughout their length and integrally united by a thickened portion, a lateral projection from the inner side of the long arm approximately midway 70 of its length, said stones being arranged to be superimposed at the corner of united walls with the long arms and short arms alternating one above the other and having their ends breaking joint in a relationship 75 in which the ends of the short arms intermediate the planes of the sides of said projections of upper and lower stones, inner wall facing stones spaced from said first 80 named stones bearing upon the projections on said first named stones and terminating out of contact with the inner faces of said first named stones, and stones forming continuations of the inner and outer wall surfaces and spaced from each other and having interengaging connections.

4. In a building wall, a series of angular corner stones each comprising a relatively long arm and a relatively short arm of approximately equal thickness throughout their length and integrally united by a thickened portion, a lateral projection from the inner side of the long arm approximately midway 90 of its length, said stones being arranged to be superimposed at the corner of united walls with the long arms and short arms alternating one above the other and having their ends breaking joint in a relationship 95 in which the ends of the short arms intermediate the planes of the sides of said projections of upper and lower stones, inner wall facing stones spaced from said first 100 named stones, a projection on each of said inner facing stones bearing upon the projections on said first named stones and terminating out of contact with the inner faces of said first named stones, and stones forming continuations of the inner and outer wall surfaces and spaced from each other and having interengaging connections leaving a 105 vertical space between the inner and outer wall portions that is continuous vertically and longitudinally and is bounded on the inner and outer sides by the thinnest portions of said stones.

5. In a building wall, a series of angular corner stones each comprising a relatively long arm and a relatively short arm of approximately equal thickness throughout their length and integrally united by a thickened portion, and a lateral projection from the inner side of the long arm approximately 110 midway of its length, said stones being ar-

ranged to be superimposed at the corner of
united walls with the long arms and short
arms alternating one above the other and
having their ends breaking joint in a rela-
tionship in which the ends of the short arms
5 are intermediate the planes of the sides of
said projections of upper and lower stones,

an outer wall facing in continuation of said
corner stones and an inner wall facing spaced
from said corner stones and said outer wall ¹⁰
facing and having interlocking connection
with said projections.
